ELLIS C. HEALY, OF EAST ORANGE, NEW JERSEY, ASSIGNOR TO INTERNATIONAL PAPER COMPANY, A CORPORATION OF NEW YORK.

HOISTING MECHANISM.

Application filed July 9, 1927. Serial No. 204,443.

This invention relates to hoisting mechanism designed for raising, lowering, and transporting bodies or articles, and has reference more particularly to mechanism for lifting the large rolls of paper from paper winding machines such as are usually employed as adjunctive to the calendar stack of paper making machines to wind up the calendered paper in roll form. 5 Such rolls are wound each on a rotary shaft driven in the winding machine, and when the roll has reached the desired size, the shaft, carrying the roll with it, is removed from the machine and deposited in a convenient place, and the shaft is removed from the roll and returned to the winding machine so that another roll of paper may be wound thereon. In some cases these rolls are some twenty feet long and of varying 10 diameter, from three to four feet more or less, and are consequently of great weight and difficult to handle, and this difficulty is the more pronounced by reason of the fact that in many cases the paper web is slit 15 longitudinally at a number of points before passing onto the winding shaft, with the result that the shaft will have wound on it a long composite roll made up of a number of shorter rolls lying closely side by side. 20 It has been the practice heretofore in removing the paper rolls from the winding machine, to couple lifting hooks carried by cables to the ends of the shaft, but this practice has been found to be objectionable in 25 that with a long roll, the weight of the paper causes the shaft and roll to sag in the middle, thereby buckling and otherwise injuring the paper; and when the roll is made up of a number of smaller closely adjacent rolls, 30 above mentioned, such sagging will crush the edges of the paper on the respective rolls, and seriously injure the same and in many cases render the paper unfit for use. 35

My invention aims to overcome these objections, and the invention consists of an improved form of hoisting mechanism characterized by the employment of roll engaging devices which will engage the roll at opposite sides, thereby giving continuous support 40 throughout the extent of the roll and effectively preventing sagging of the same; and

in the specification to follow the invention will be described in detail, and the novel features thereof will be pointed out in the appended claims.

55

In the accompanying drawings:

Fig. 1 is a side elevation of the improved hoisting mechanism;

Fig. 2 is a top plan view of the same, showing a paper roll engaged by the gripping tongs;

Fig. 3 is an end elevation of the same.

Referring to the drawings:

The mechanism comprises as its main features a longitudinally extending supporting frame member 1, a series of gripping tongs 2 depending from said frame member and carrying at their lower ends longitudinally extending roll engaging members 3 adapted to engage the paper roll 4 on opposite sides of the same, and a pressure-fluid operated cylinder and piston 5 supported by the frame member and operatively connected with the gripping tongs for actuating the same, the said frame member 65 being adapted to be connected with a suitable hoisting tackle 6 for raising and lowering and transporting the same.

In the present instance the longitudinal frame member is constructed of two channeled bars 1^a fastened together side by side in spaced relations, thereby forming a unitary frame structure, to the upper side of which hoisting sheaves 5^a are swiveled to receive cables 5^b of the hoisting tackle.

The gripping tongs 2, of which there are six in the example of the invention illustrated, comprise each a pair of opposing tong arms 8 pivoted between their ends as at 9 in forked bracket arms 10 depending from the underside of the frame bar, the said sets of forked arms being spaced from each other along the length of the bar as best shown in Figs. 1 and 2. At their upper ends the tong arms 8 are pivoted to the outer end respectively of toggle links 11, whose inner ends are pivoted as at 12 to a block 13, and vertical links 14 are pivoted at their lower ends to the respective blocks and extend upwardly between the bracket arms 10, the construction being such that when the links are raised, the toggle links will draw the

80

100

upper ends of the tong arms inwardly toward each other, thereby moving their lower ends outwardly away from each other and opening the tongs, and when the links 5 are lowered, the motion of the parts being reversed, the tongs will be closed, all as will be presently more particularly described.

The lower ends of the tong arms are connected together by through bolts 15, and 10 rollers 16 are rotatably mounted on the bolts between the respective tong arms, which rollers are adapted to engage on opposite sides of the paper roll as clearly shown in Figs. 2 and 3. The rollers thus arranged 15 end to end, constitutes the longitudinally extending roll engaging members 3 before alluded to as being carried by the lower ends of the tong arms, and afford when engaged with the paper roll, a support for the same 20 at its opposite sides extending throughout its length.

The links 14 are raised and lowered to respectively open and close the gripping tongs by means of the cylinder and piston 25 before alluded to, the cylinder being fixedly supported in a horizontal position on the upper side of the frame member at one end of the same, and the piston rod 16^a of the piston being connected with an actuating 30 member or bar 17 extending along the upper side of the frame bar 1 and movable longitudinally in guides 18 extending upwardly from said frame bar, the said actuating bar being in the present instance formed of 35 two rails connected fixedly together side by side with a longitudinal space between them. Bolts 19 are extended at intervals through said rails and the intervening space, which bolts are engaged loosely in the upper forked 40 ends 20 of upper limbs 21 of elbow levers 22, which elbow levers are pivoted as at 23 on horizontal transverse axes between the channel bars 1^a of the frame bar, the lower limbs 24 of said elbow levers being pivoted 45 at their extremities to the upper ends of the vertical links 14. As a result of this form and arrangement of the parts, when the piston is moved in one direction in the cylinder, say to the right in Fig. 1, the elbow 50 levers will be rocked clockwise and the vertical links 14 will be raised and the tongs thereby closed; and when the piston is moved in the opposite direction, the motion 55 of the parts being reversed, the tongs will be opened.

The cylinder is supplied with fluid under pressure from a flexible supply pipe 25 which communicates with a valve casing 26, from which valve casing a pipe 27 leads to the 60 right-hand end of the piston, Fig. 1, and a pipe 28 leads to the left-hand end of the piston, the said valve casing being provided with a two-way valve 29 adapted when turned to different positions, to admit pressure 65 respectively to the ends of the cylinder

and open the opposite ends to exhaust. The valve has connected with it operating arms 30 from which depend chains or cords 31 to a point within convenient reach of the attendant on the floor.

70

In the operation of the mechanism in removing a paper roll from the winding machine, the hoisting tackle is manipulated to bring the hoisting mechanism vertically above the winding machine, and the valve 75 controlling the admission of pressure fluid to the operating cylinder and piston is turned to a position to open the gripping tongs. The hoisting tackle is now operated to lower the mechanism until the roll engaging rolls 80 on the lower extremities of the tongs reach a point below the center of the paper roll, whereupon the valve is operated to close the gripping tongs, in which action the longitudinal rolls on the tongs will engage with 85 the opposite sides of the paper roll below its center as shown in Fig. 4. The shaft carrying the roll is now released from its bearing in the winding machine, or it may have been previously released, and the hoisting 90 tackle is operated to raise the hoisting mechanism, in which action the paper roll with the shaft therein will be lifted from the winding machine. The hoisting tackle is then operated to transport the mechanism 95 and paper roll supported thereby to the desired position for its storage, and the mechanism is lowered so as to deposit the roll on the floor or on other appropriate support. The gripping tongs are now opened and the 100 hoisting mechanism raised, and the shaft is removed from the roll and placed in the winding machine for the winding of the new roll of paper.

100

As hereinbefore pointed out, due to the 105 fact that the roll of paper is in the handling of the same by the hoisting mechanism, engaged on its opposite sides throughout its extent by the longitudinal rolls on the gripping tongs, the paper roll will be effectually supported and sagging will be prevented. This action I deem of advantage and importance, more particularly where long and heavy paper rolls are handled made up of 110 aligned shorter rolls, as 4^a, Fig. 1, as the shorter rolls will be maintained in straight alignment, and crushing of the edges of the paper prevented.

110

While in the foregoing description and accompanying drawings I have set forth the invention in the particular detailed form and arrangement of parts which I prefer to adopt, it will be understood that these details may be variously changed and modified without departing from the spirit of the invention; and further it will be understood that the invention is not limited to any particular form or construction of the parts, except in so far as such limitations are 115 specified in the claims.

120

125

130

Having thus described my invention, what I claim is:

1. In a hoisting mechanism for handling paper rolls, the combination of an elongated supporting frame adapted to be raised and lowered, gripping arms depending at intervals from said frame in two opposed rows and movable to and from each other, elongated roll engaging members connected to the lower ends of said gripping arms and extending opposite and parallel to each other to engage the opposite sides of the roll, a pressure fluid cylinder and piston mechanism supported on said frame, a member operatively connected with said piston to be reciprocated thereby, and operative connections between said reciprocating member and the gripping arms, said connections being such that on the movement of the reciprocating member in one direction, the opposed gripping arms will be moved toward each other and the elongated members caused to grasp the roll on opposite sides, and on the movement of the reciprocating member in the opposite direction, the elongated members will be moved away from each other to release the roll.
  2. In a hoisting mechanism, the combination of a supporting mechanism adapted to be raised and lowered, pairs of opposed gripping arms supported by said frame and movable to and from each other, rotatable rollers carried by and extending longitudinally between said arms and constituting opposing longitudinal members adapted to engage on opposite sides of the object to be lifted, and means for moving the arms to and from each other.
  3. In a hoisting mechanism, the combination of a supporting frame adapted to be raised and lowered, pairs of opposing gripping arms supported by said frame and movable to and from each other, through bolts extending through said arms, rolls rotatably mounted on said bolts between the arms, and means for moving said arms to and from each other.
  4. In a hoisting mechanism, the combination of a supporting frame adapted to be raised and lowered, pairs of opposed gripping arms pivotally supported between their ends on said frame and adapted at their lower ends to engage the body to be lifted, toggle links pivoted to the upper ends of said arms, a pressure fluid actuated cylinder and piston supported by the frame, and an actuating bar operated by said cylinder and piston and operatively connected with the toggle links.
  5. In a hoisting mechanism, the combination of a supporting frame adapted to be raised and lowered, pairs of opposed gripping arms pivotally supported between their ends on said frame and adapted at their lower ends to engage the body to be lifted, toggle links pivoted to the upper ends of said arms, a pressure fluid actuated cylinder and piston supported by the frame, an actuating bar operated by said cylinder and piston, and links operatively connected with the bar and with the toggle links.
  6. In a hoisting mechanism, the combination of a supporting frame adapted to be raised and lowered, pairs of opposing gripping arms pivotally supported between their ends on the frame and adapted at their lower ends to engage the body to be lifted, toggle links pivoted to the upper ends of said arms, vertical links pivoted at their lower ends to the toggle links, a pressure fluid actuated cylinder and piston supported by the frame and operatively connected with the actuating bar, and elbow levers operatively connected with said actuating bar and with said links.
  7. In a hoisting mechanism, the combination of an elongated supporting frame, bracket arms depending at intervals from the same, tong arms pivoted between their ends to said bracket arms, longitudinally extending members carried by the lower ends of the tong arms and adapted to engage on opposite sides of the object to be lifted, toggle links pivoted to the upper ends of the tong arms, links pivoted to the toggle links, a longitudinally extending endwise moveable actuating bar supported by the frame, elbow levers pivoted to the actuating bar and to said links, and a power mechanism for moving the actuating bar endwise.
- In testimony whereof, I have affixed my signature hereto.

ELLIS C. HEALY.
